(57) CLAIM

I claim the ornamental design for a concrete curb form spreader and spacer, as shown.

DESCRIPTION

FIG. 1 is a front perspective view of the concrete form spacer and spreader showing my new design; FIG. 2 is an end elevational view thereof;

FIG. 3 is an opposite end elevational view thereof;

FIG. 4 is a top plan view thereof;

FIG. 5 is a left side elevational view thereof;

FIG. 6 is a bottom plan view thereof; and,

FIG. 7 is a right side elevational view thereof.
